JAMES SMITH, OF CENTREVILLE, MARYLAND.

BRICK-LAYER'S PLUMB-LEVEL, &c.

SPECIFICATION forming part of Letters Patent No. 402,360, dated April 30, 1889.

Application filed August 31, 1888. Serial No. 284,310. (No model.)

To all whom it may concern:

Be it known that I, JAMES SMITH, of Centreville, in the county of Queen Anne and State of Maryland, have invented certain new and useful Improvements in Brick-Layers' Combined Plumb-Level and Guide-Line Holder, of which the following is a specification.

The objects had in view in this invention are to provide a convenient and accurate instrument for brick-layers' use to preserve a true corner joint, and consequently the laying of the bricks in level courses, while it combines great facility and expedition in handling, resulting in more durable and permanent work, every brick being left in a good mortar-bed and not in a shattered and loose condition; and to these ends the invention consists of a frame or upright having applied to it a series of angle castings or guides adapted to fit the corners of the prospective walls of a building, and which frame or upright is also provided or armed with graduated plates, one at each of two sides, and with line securing or holding slits or notches. The frame or upright also has applied to it clamps which effect a hold upon the bricks and pass through said frame or upright, their outer ends receiving keys or wedges which effect the holding of the clamps in place and which are adapted to be readily withdrawn from said clamps. Applied to each side of the frame or upright is a plumb-level or bob, as also a spirit-level, all substantially as herein-after more fully set forth, and pointed out in the claims.

In the accompanying drawings, Figure 1 is a view in elevation, showing my brick-layer's combined plumb-level and guide-line holder as applied for use. Fig. 2 is an enlarged plan view of the same, and Fig. 3 is a horizontal section on the line $x x$ of Fig. 1.

In the embodiment of my invention I employ an upright, A, which in the present instance consists of two boards or pieces, $a a$, joined together at right angles to each other. The outer side of each board or piece a is provided with a plate, a' , graduated in inches and fractions of inches throughout its entire length, while to the same sides of said boards or pieces are also applied, at suitable intervals apart along their length, guides or castings B B. The guides or castings are formed in

pairs, the guides of each pair crossing each other at right angles, and one extending from each of two adjacent faces or sides of the upright A, as shown, whereby the same is adapted for application to the corner of a wall of a building or inclosure. The inner ends of the guides or castings B are secured or bolted to the inner sides of the boards or pieces $a a$ of the upright A at their inner edges.

In the boards or pieces of the upright A is a series of slits or notches, $b b$, which are arranged at suitable intervals apart for the insertion and holding therein of the guide-line used in laying the courses of bricks, it being understood that an implement is applied to the opposite corners of the wall being put up.

Applied to the upright A, near its lower end and a short distance above the same—say a space apart equal to about four courses of bricks—and to the outer side of each board or piece $a a$ thereof, are clamps C C, for securing the upright in position. Similarly applied to the upright A are also additional guides, B' B'. The connection of the bottom guides, B' B', with the upright or frame A is effected by means of adjusting screw-bolts and thumb-nuts $b' b'$, respectively, 80 the screw-bolts connecting with the frame or upright A and passing through apertures in lateral extensions of the guides, while the thumb-nuts fit upon the screw-bolts, as shown. This arrangement permits of the adjustment 85 of the guides to the bricks, so as to allow for any little irregularities upon their surfaces in plumbing the instrument. The inner ends of the clamps C C are passed through apertures in the boards or pieces $a a$ of the upright A and project therefrom, and are provided with apertures or eyes c c, which receive keys or wedges c' c', to effect the holding of the same in position. The outer ends of the clamps are extended at right angles to 95 their main or body portions, and are thus adapted to enter the green mortar of the coincident joints of the wall and be clamped therein as the wedges or keys c' c' are inserted and driven home in the apertured ends of 100 said clamps. The keys or wedges c' c' are suspended by cords or wires c² c², connecting with the upper end of the upright A in any suitable way. It may be as shown. By this arrange-

ment the keys or wedges may be readily withdrawn or removed from the clamps by pulling or drawing upon the cords or wires at the top or upper end of the upright—*i. e.*, after the putting up of the wall to that height by the workman from the inside—it then, of course, being required to shift the implement, thus permitting of the ready manipulation of the implement, so as to allow of the placement of the same and its elevation to a higher point as the wall advances in height. D D are plumb bobs or levels, one disposed upon each outer side of the upright A, as shown. Upon each outer side of the upright A is also provided a spirit-level, E, for use in event the plumb bobs or levels are incapable of use, as in windy weather.

From what has been disclosed the use of this invention is apparent. It is only necessary to remark, possibly, that with two uprights, A, applied to the base of each of the opposite corners of the prospective wall, and the required connection between the wall and the clamps effected in the manner as shown and as partly above described, the keys or wedges are inserted in the apertured projecting ends of said clamps, which will secure the uprights in position. The guideline is now stretched, being inserted at its ends into the required slits or notches b b of the uprights, and the implement is now ready for the laying of the bricks in the required courses, the uprights with their guides, with the aid of the plumb-bob or spirit-level, always preserving the corner bricks plumb and level, together with that of the laying of the intermediate courses.

Having thus fully described my invention, what I claim, and desire to secure by Letters 40 Patent, is—

1. The combined plumb-level and guideline holder consisting of an angle upright provided with a series of angle castings or guides to fit the angle or corner of a wall and with clamps detachably connected there-

with to engage with or enter the joints between the bricks of the wall, substantially as and for the purpose set forth.

2. The combined plumb-level and guideline holder provided with angle guides or castings adapted to fit the implement to the angle or corner of a wall, the bottom guides being adjustable, substantially as set forth.

3. The combined plumb-level and guideline holder having a graduated upright provided with the guide-line slits or notches, angle castings or guides to fit the angle or corner of a wall, and clamps to engage with or enter the joints between the bricks of the wall and confined to the upright by keys or wedges, substantially as and for the purpose specified.

4. The combined plumb-level and guideline holder having an upright provided with angle castings or guides to fit the angle or corner of a wall, clamps to engage with or enter the joints between the bricks of the wall, and keys or wedges suspended from the top or upper end of the upright and engaging with apertures in the inner ends of the clamps, substantially as and for the purpose specified.

5. The combined plumb-level and guideline holder consisting of the graduated upright having a series of guide-line slits or notches, the angle castings or crossing-guides applied to the upright and adapted to fit the corner or angle of a wall, the clamps to engage with or enter the joints between the bricks of the wall and provided at their inner ends with apertures, the keys or wedges engaging with the apertures of the clamps, and the suspending cords or wires of the keys or wedges connected or applied to the top or upper end of the upright, substantially as set forth.

JAMES SMITH.
